UNITED STATES PATENT OFFICE.

JESSE B. BRONSTEIN AND CHARLES E. WALLER, OF ALLENTOWN, PENNSYLVANIA,
ASSIGNORS TO INDEPENDENT NON-FREEZING POWDER COMPANY, OF NEWARK,
NEW JERSEY, A CORPORATION OF NEW JERSEY.

NITRO-STARCH EXPLOSIVE.

1,188,246.

Specification of Letters Patent. Patented June 20, 1916.

No Drawing.

Application filed July 6, 1914. Serial No. 849,259.

To all whom it may concern:

Be it known that we, JESSE B. BRONSTEIN and CHARLES E. WALLER, citizens of the United States, and residents of Allentown, 5 Lehigh county, Pennsylvania, have invented certain Improvements in Nitro-Starch Explosives, of which the following is a specification.

Our invention relates to nitro-starch explosives.

Heretofore, nitro-starch explosives have been made containing nitro-starch as the explosive base (and in using the term "nitro-starch explosives" we refer to explosives 15 such as employ nitro-starch as an explosive base and are used for blasting purposes), nitrate of soda as the oxygen carrier and suitable quantities of an anti-acid such as calcium carbonate and of a waterproofing 20 material such as paraffin oil. These powders have been graded to suit conditions encountered in practice, by varying the percentage of nitro-starch and nitrate of soda. This type of explosive has been quite widely 25 used and found satisfactory for many purposes.

Ordinarily in order to get the best results from the explosive, it is desirable that the shattering force or brisance and the propellant force of the explosive be fairly well balanced. For use, however, in underground operations, where the rock is extremely hard, it is necessary to have an explosive, the energy of which is chiefly developed as shattering force or brisance, and the object of the present invention is to provide a nitro-starch explosive, cheap and efficient, but with greater relative shattering force or brisance than the nitro-starch pow- 40 ders as heretofore made.

We have discovered that by substituting, within certain limits, barium nitrate for a portion of the sodium nitrate ordinarily employed as the oxygen carrier in nitro-starch powders, a certain proportion of the propellant force of the explosive can be converted into shattering force or brisance. In

fact, experiment has shown that the shattering force of nitro-starch explosives may be increased about twenty per cent. by substituting about thirty per cent. of barium nitrate for a like proportion of sodium nitrate ordinarily employed as the oxygen carrier.

The substitution of barium nitrate for a portion of the sodium nitrate oxygen carrier has these advantages. In the first place, it has a smaller oxygen excess than sodium nitrate and for this reason gives an increased temperature of explosion in those explosives which would otherwise contain a considerable excess of free oxygen; secondly, it appears to carry its oxygen in a more readily available form; thirdly, the specific gravity of barium nitrate is greater than that of sodium nitrate, thereby resulting in a denser charge which results in a greater shattering force by reason of the fact that the smaller the charge chamber for a given amount of explosive energy, the more violent will be the action of the explosive on the surrounding matter. By reason of the smaller oxygen excess referred to, the employment of barium nitrate in the manner described is particularly useful in powders of low grade, where the relatively smaller amounts of the explosive base lead to oxygen excess, and also in powders where oxygen excess is due to any other cause, as for example where a portion of the nitro-starch has been replaced by other agents, such for example as a mixture of ammonium nitrate and trinitrotoluene as described in our application for patent filed August 7, 1913, Serial No. 783,601. But in the broader aspect of our invention, we do not wish to be confined to the employment of barium nitrate with any specific nitro-starch powder, as said material can be usefully employed as a substitute for a portion of the oxygen carrier in nitro-starch explosives generally.

We have found that the addition of barium nitrate to nitro-starch explosives increases

the susceptibility of the explosive to the effect of the detonating cap, and experiment has indicated that the facility with which the detonating wave passes through the powder is also increased by the presence of the barium nitrate, thus making it possible to secure better results in blasts where long charges of powder are employed. The presence of barium nitrate is of further advantage in nitro-starch explosives in that it reduces the tendency to absorb moisture.

There are of course limits to the proportions of barium nitrate which can be successfully employed and we believe that said ingredient could not be successfully employed in excess of forty per cent. (40%) by weight of the entire explosive. As one example of a nitro-starch powder employing barium nitrate in the manner hereinbefore described, we give the following formula:

Nitro-starch	40.0%
Sodium nitrate	37.7%
Barium nitrate	20.0%
Calcium carbonate	1.5%
Paraffin oil	.8%
	100.0%

In some instances it is desirable to increase the shattering force or brisance of the explosive beyond that possessed by such a mixture as is set forth in the formula just given, and we have found that if in addition to the other ingredients including barium nitrate, a proportion of sulfur be added to the mixture, we can obtain the increased shattering force desired. We believe that this result is due to the reaction which occurs on explosion between the barium nitrate and the sulfur, which results in a marked and unusual increase of temperature, a result which is not approached or attained when either the barium nitrate or the sulfur is alone in the explosive. For the purpose stated the sulfur should not be used in quantities substantially in excess of eight per cent. (8%) by weight of the entire mixture. As an illustration of a nitro-starch powder employing barium nitrate and sulfur in the manner described, we give the following formula:

Nitro-starch	40.0%
Sodium nitrate	34.7%
Barium nitrate	20.0%
Calcium carbonate	1.5%
Paraffin oil	.8%
Sulfur	3.0%
	100.0%

As an illustration of a nitro-starch powder including ammonium nitrate-trinitrotoluene

mixture and also employing our present invention, we give the following formula:

Nitro-starch	40.0%
Ammonium nitrate trinitrotoluene mixture	20.0%
Barium nitrate	20.0%
Sodium nitrate	17.7%
Calcium carbonate	1.5%
Paraffin oil	.8%
	100.0%

We are aware that it has heretofore been proposed to make use of barium nitrate as an oxygen carrier in certain types of explosives, but we are unaware that this has ever been done in connection with powders of the class with which we are working, or that it has ever been done in connection with nitro-starch powders of the detonating type, and we believe that we are the first to suggest the employment of barium nitrate as a substitute for a portion of the sodium nitrate oxygen carrier ordinarily employed with nitro-starch powders. Further we believe that the advantages incident to the use of barium nitrate hereinabove set forth have not heretofore been developed and are such as would not have been anticipated by those skilled in the art.

As this application possesses matter in common with an application filed by us August 7, 1913, Serial No. 783,601, it is to be treated as a continuation of said prior application as far as the common subject-matter is concerned.

We claim:

1. A detonating explosive containing nitro-starch and barium nitrate; the barium nitrate being not less than twenty per cent. (20%) nor more than forty per cent. (40%) by weight of the entire explosive.
2. A detonating explosive containing nitro-starch, sodium nitrate, and barium nitrate; the barium nitrate being not less than twenty per cent. (20%) nor more than forty per cent. (40%) by weight of the entire explosive.
3. A detonating explosive containing nitro-starch, sodium nitrate, barium nitrate and sulfur.
4. A detonating explosive containing nitro-starch, sodium nitrate, barium nitrate not exceeding forty per cent. (40%) by weight of the entire mixture, and sulfur not substantially exceeding eight per cent. (8%) by weight of the entire mixture.

In testimony whereof, we have signed our names to this specification, in the presence of two subscribing witnesses.

JESSE B. BRONSTEIN.

CHARLES E. WALLER.
